UNITED STATES PATENT OFFICE

MICHAEL J. TRACY, OF ST. LOUIS COUNTY, MISSOURI

WINDOW

Application filed March 14, 1930. Serial No. 435,689.

This invention relates to windows, and has special reference to barred windows for use in institutions and elsewhere so that, while the windows admit light and are capable of adjustment to permit the passage of air, it is impossible for persons to pass through the windows.

An object of the invention is to provide a window having panes for the passage of light and having openings for the passage of air, and closures for said openings, in combination with means for moving the closures to open positions to permit the passage of air and to closed positions to exclude the air, and arranged so that, when the closures are in closed position, they will cooperate with the panes to prevent rain and snow, etc. from passing through the windows.

Another object of the invention is to provide a window embodying the construction and capable of the operation mentioned, in combination with means for barring and preventing the passage of persons through the windows even though the panes should become broken and the closures should be removed.

Other objects will appear from the following description, reference being made to the accompanying drawings, in which—

Fig. 1 is a vertical longitudinal sectional view of my improved window.

Fig. 2 is an outside elevation of the window.

Fig. 3 is an enlarged vertical sectional view of a window embodying the present invention, showing the mechanism for operating the closures to open and close the ventilating air passages.

Fig. 4 is a horizontal sectional view approximately on the line 4—4 of Fig. 3.

Fig. 5 is a horizontal sectional view approximately on the line 5—5 of Fig. 3.

Fig. 6 is an enlarged sectional view showing the construction of the closures for the window vents.

The window frame may be constructed in various ways and is preferably made of metal. In the embodiment shown, there is at each side of the window opening a vertical angle bar rigidly secured to the wall of the building. These angle bars may be rigidly at-

tached to the building wall by any desired fastening means, as by embedding the lateral flanges 1 of the angle bars, while the angle bar flanges 2 extend inwardly toward the inner side of the wall. A series of metallic bars 3 extend transversely of the window opening and have their ends rigidly attached to the angle bar flanges 2. These bars 3 are incapable of longitudinal movement and cannot be bent without the application of extraordinary force requiring powerful machinery or levers, such as are never available to the inmates of the institutions in which the windows are used and which are never readily available for use from the outside. The ends of these bars 3 may be extended through holes in the flanges 2 so that the ends of said bars 3 are close to the surfaces of the building wall 4 at the sides of the window opening. These bars may be specially constructed with longitudinal ribs or flanges 5 along their outer sides and with longitudinal flanges 6 along their inner sides. These bars 3 may be of duplicate construction and cut to the proper length for use in the windows as desired.

Each window frame also has at each vertical side thereof a frame member composed preferably of substantially impenetrable sheet metal shaped to provide a wall 7 having along its inner edge a flange 8 attached to the building wall 4. The outer edge of the wall 7 extends substantially beyond the inner edge of the flange 2 and may be provided with notches or holes through which the bars 3 may be extended in order to obtain a more rigid and secure construction.

The outer portion of each side frame member is composed of a metallic sheet 9 having its outer portion shaped to provide a flange 10 rigidly secured to the building wall 4 or to the angle bar member 1—2, or secured both to the building wall and to said angle bar member. The plates 9 extend inwardly beyond the outer edges of the plates 7 and are spaced laterally therefrom so that there is sufficient space 11 between the plates 7 and 9 (Fig. 4) for the mounting and for the operation of the connections for moving the closures for the ventilating openings to closed and to open positions. The inner edges of the

plates 9 are shaped to provide downwardly and inwardly inclined shoulders 12 which form seats for the movable closures when said closures are in closed positions; and to 5 provide edges 13 inclining downwardly and outwardly from intersection with the shoulders 12. The lower ends of the edges 13 are approximately in the same plane as the next lower shoulders 12, respectively. Appropri- 10 ate notches 14 for receiving the ends of the bars 3 are between the shoulders 12 and the lower ends of the inclined edges 13.

Corresponding to the series of bars 3 a series of inclined bars 15 is provided and 15 rigidly attached to the window frame members 7 opposite the lower edges of the shoulders 12. These bars 15 may be made of hard metal or other appropriate material, and, if desired, may be covered by covers 16. When 20 thus arranged, the upper edges of the covers 16 are approximately in alinement with the shoulders 12, being inclined downwardly and inwardly from said shoulders 12. A series of window sash holders is attached to the 25 frame members 7 against the inclined edges 13. As shown, each of these window sash holders comprises a channel 17 having its lower end seated upon the flange 5 and having its upper end seated against the bar 15. 30 Thus the channels 17 are arranged in pairs, one channel of each pair being secured to the plate 7 at one side of the window frame, and the other channel being secured to the plate 7 at the opposite side of the window frame. 35 These channels are parallel, so that the transparent or translucent panes 18 may be placed therein with their lower edges seated upon the flanges 5 and their upper edges seated against the upper edges of the bars 15. Putty 40 or other sealing material 19 fills the channels 17 at the outer sides of the panels 18, thus providing impervious weatherproof joints and securing the panels 18 in proper position in their supporting frames. It is now clear 45 that these panels 18 are arranged on the louver principle, including downwardly and outwardly so as to discharge therefrom rain and other substances coming into contact with the outer surfaces thereof. This leaves a 50 space between the upper edge of each pane 18 and the adjacent bar 3. These spaces are provided with closures which are movable to positions to open and to close said spaces. Each closure comprises an upper metallic 55 plate 20, a lower metallic plate 21 having along its lower margin a downturned edge 22 and along its upper margin a downturned edge 23. Between these plates 20 and 21 a resilient metallic strip 24 is secured, so that 60 the assembly comprising said three plates 20, 21 and 24 is a unitary member. The lower marginal edge 25 is flexed downwardly so that when the device is in closed position, the edge 25 seats closely against the bar cover 65 16, while the flange 22 is against the upper

edge of said cover 16 and the flange 23 is against the lower edge of the bar flange 6. Each of these closures has rigid therewith at each end an upwardly extended flange 26.

A bar 27 is mounted for vertical move- 70 ments at each side of the window frame. These bars 27 are enclosed and covered by the plates 9. The bars 27 are connected with the respective window vent openings at each end by pairs of links 28 having their lower 75 ends pivoted to said bars 27 and their upper ends pivoted to the flanges 26. Between each pair of links 28 there is a support 29. The supports 29 are preferably cylindrical in cross-section and have their outer ends rigid 80 with the plates 9 and their inner ends rigid with the plates 7. Thus, these supports 29 extend across the spaces 11 between the two links 28 of each pair of said links.

The lower ends of the bars 27 have pin- 85 and-slot connection 30 with an arm 31 rigid with a rock shaft 32. The rock shaft 32 has its ends journalled for rocking movements in the plates 7 and has at one end a lever 33 whereby said shaft 32 may be rocked.

The upper end of each window frame com- 90 prises a plate shaped to provide a horizontal portion 34 and a portion 35 extending downwardly and outwardly to engagement with the flange 5 of the uppermost bar 3. 95 The joint between the bar 3 and said plate may be rendered impervious by solder 36 or other suitable material. The lower edge of the part 35 is bent outwardly and upwardly to provide a portion 37 abutting against a bar 100 38 anchored in the building wall.

The lower portion of each window frame com- 105 prises a plate 39 inclining upwardly and outwardly to engagement with the lowermost bar 3, an impervious joint being obtained by a quantity of solder 40 or other appropriate sealing material. The plate 39 has a down- 110 wardly and out-extended portion 41 secured in some appropriate fashion to the lower wall of the window opening.

The panes 18 may be made of glass or other transparent material and, if desired, may be made of so-called non-breakable glass. It is impossible for the occupants of the building to remove these panes, because 115 the upper edges thereof are overlapped by the outer edges of the parts 16 which cannot be detached from the bars 15.

When it is desired to open the ventilators, 120 the lever 33 is moved downwardly to the position indicated by dotted lines in Fig. 3, thus moving upwardly both bars 27 and thereby moving the links 28 along the support 29. The first portion of the upward movement of the bars 27 raises the closures for the venti- 125 lating openings sufficiently to disengage the flanges 22 from the bar structures 15—16. Continued upward movement of the bars 27 effected by rocking the shaft 32, moves the 130 closures inwardly and downwardly onto the

bar structures 15—16, which constitute rigid supports for the closures in the open position of the latter. When it is desired to close the vent openings, it is only necessary to raise 5 the lever 33, thereby turning the shaft 32 in a direction to move the bars 27 downwardly, causing the links 28 to carry the closures to the closed positions in which the flanges 22 are seated against the bar members 16, and 10 in which the flanges 23 are seated against the flanges 6.

These windows may be made so that they do not give the appearance of barred windows, but possess more the appearance of ornamental structures. These desirable results and effects may be obtained without sacrificing any of the mechanical functions of the windows. The construction and arrangement and relationship of the parts may be 20 widely varied without departure from the nature and principle of the invention. I do not restrict myself unessentially, but what I claim and desire to secure by Letters Patent is:—

25 1. A window comprising a rigid window frame, a series of downwardly and outwardly inclined window panes rigidly mounted in said frame, series of spaced bars rigid with said frame adjacent to the upper and lower 30 edges respectively of said panes, a series of closures for the spaces between said bars, mechanism for moving said closures to and from positions to close the spaces between said bars, and a device for operating said 35 mechanism.

2. A window comprising a series of translucent panes forming a louver in which the adjacent edges of the panes are spaced apart, rigid metallic bars extending along the upper 40 and lower edges of said panes, closures for closing the spaces of the louver, and mechanism for operating said closures simultaneously to close or to open said spaces.

3. A window comprising a frame, a series 45 of bars mounted transversely in said frame and each having a longitudinal flange along its outer portion, an additional series of bars in said frame spaced inwardly from said first named bars, translucent panes mounted rigidly in said frame and inclining downwardly and outwardly from said second named bars to said first named bars and having their lower edges adjacent to said flanges, and means preventing removal of said panes.

50 4. A window comprising a frame, a series of bars mounted transversely in said frame and each having a longitudinal flange along its outer portion, an additional series of bars in said frame spaced inwardly from said first named bars, translucent panes mounted rigidly in said frame and inclining downwardly and outwardly from said second named bars to said first named bars and having their lower edges adjacent to said flanges, means preventing removal of said panes,

and movable closures for opening and closing the spaces between said bars.

5. A window comprising a frame, a series of bars mounted transversely in said frame and each having a longitudinal flange along 70 its outer portion, an additional series of bars in said frame spaced inwardly from said first named bars, translucent panes mounted rigidly in said frame and inclining downwardly and outwardly from said second named bars to said first named bars and having their lower edges adjacent to said flanges, means preventing removal of said panes, movable closures for opening and closing the spaces between said bars, links having their ends pivoted to said closures respectively, sliding bars pivoted to the opposite ends of said links, and means for operating said sliding bars and thereby said links to move said closures to positions to open and to close said 85 spaces as desired.

6. A window comprising a rigid frame, two transverse series of rigid bars mounted in said frame in spaced relationship, elements located in said frame rigidly with respect to said bars and forming a louver window, and devices for opening and closing the spaces between said elements of said louver window.

7. A louver window comprising a rigid 95 frame, a series of panes rigidly supported in said frame and forming a louver window, two series of bars rigidly mounted in said frame at the upper and lower edges of said panes respectively and being spaced apart 100 to leave louver openings, and mechanism for opening and closing said openings.

8. A louver window comprising a rigid frame, a series of panes rigidly supported in said frame and forming a louver window, two series of bars rigidly mounted in said frame at the upper and lower edges of said panes respectively and being spaced apart to leave louver openings, closures for said openings, and mechanism for operating said closures simultaneously to open or to close said openings.

9. A louver window comprising a rigid frame, a series of translucent panes forming 115 a louver window in said frame, rigid metallic bars in said frame at the upper and lower edges of said panes respectively and spaced apart to form louver openings, closures for said openings, links pivoted to said closures, 120 bars for operating said links, and mechanism for operating said bars and thereby said links to move said closures to positions to open and to close said openings.

10. A louver window having openings 125 therethrough, sliding closures for opening and closing said openings, links pivoted to said closures, sliding bars having pivotal connection with said links, and mechanism for moving said bars and thereby said links 130.

to slide said closures to positions to open and to close said openings.

11. A louver window having openings therethrough, sliding closures for opening and closing said openings, links pivoted to said closures, sliding bars having pivotal connection with said links, mechanism for moving said bars and thereby said links to slide said closures to positions to open and to close said openings, and means for controlling the movements of said links to require proper sliding movements of said closures.

12. A louver window comprising a rigid frame, means forming a louver in said frame, sliding closures for the openings through said louver, a sliding bar enclosed in each side of said frame, mechanism for moving said bars longitudinally in upward and downward directions, and links connecting said bars with said closures for sliding said closures to positions to open and to close the louver openings.

13. A louver window comprising a rigid frame, a series of panes forming a louver in said frame, rigid metallic bars extending along the upper and lower edges of said panes and leaving the intermediate portions of said panes unobstructed, and means sealing the joints between said panes and said frame.

14. A louver window comprising a rigid frame, a series of panes forming a louver in said frame, rigid metallic bars extending along the upper and lower edges of said panes and leaving the intermediate portions of said panes unobstructed, means sealing the joints between said panes and said frame, and mechanism for opening and closing the spaces between said panes.

40 MICHAEL J. TRACY.
